UNITED STATES PATENT OFFICE.

CHARLES C. CARPENTER, 2d, AND LUCIEN A. BROTT, OF GROTON, NEW YORK, ASSIGNEES TO L. A. BARBER & CO., OF SAME PLACE.

PROCESS OF MAKING BARRELS OF MUSICAL INSTRUMENTS.

SPECIFICATION forming part of Letters Patent No. 410,875, dated September 10, 1889.

Application filed February 13, 1889. Serial No. 299,765. (No model.)

To all whom it may concern:

Be it known that we, CHARLES C. CARPENTER, 2d, and LUCIEN A. BROTT, of Groton, in the county of Tompkins and State of New York, have invented certain new and useful Improvements in the Process of Making Rolls for Musical Instruments of all Kinds; and we do hereby declare the following to be a full, clear, and exact description of the invention, such as will enable others skilled in the art to which it pertains to make and use it, reference being had to the accompanying drawings, which form part of this specification.

Our invention relates to an improvement in the manner of making barrels or cylinders for music-boxes and other musical instruments for which rolls can be used to produce the tunes; and it consists in laying out a scale on a flat plate instead of upon a cylinder, and securing to its surface small raised points to correspond with the tune desired to be produced, this plate with points being used as a pattern from which a matrix is made to receive the deposit of metal by the electrotyping process, then bending the electrotype so as to form it into a cylinder, as will be more fully described hereinafter.

The object of our invention is to form the barrels or cylinders of musical instruments of different kinds by making electrotypes from flat patterns, and then shaping the electrotypes into barrels or cylinders, for the purpose not only of forming the cylinders much more cheaply and rapidly than has heretofore been done, but by this means securing such accuracy as to make the barrels or cylinders interchangeable, either by changing the whole barrel or the electrotype shell, which may be slipped on or off some suitable core or drum.

Figure 1 represents a flat pattern from which the electrotypes are formed. Fig. 2 is an end view of a cylinder which is formed by bending the electrotype into shape.

45 A represents the flat plate upon which the

scale is first laid out, and to which the projecting points are secured in any suitable manner, as indicated by the scale. This plate having the points attached then forms the pattern from which any suitable number of electro- 50 types are formed. The electrotypes will in all cases be made sufficiently thin to be readily formed into a cylinder C, as shown in Fig. 2. These cylinders need not necessarily be made by electrotyping alone, for they may be formed 55 of rubber, celluloid, or any other material which will answer the purpose, and they will be cast, blown, or otherwise formed from the flat plate which is made in the first instance. If so desired, the process may be carried out 60 by swaging thin copper or other metal with dies; or a thin casting of some metal may be made, the same being formed into a cylinder, as above described; or the cylinder can be made by using the above-named flat plate or 65 pattern in getting a matrix or mold of material, which can be formed into a cylinder previous to the electrotyping process.

By the construction here described it will readily be seen that after the pattern is once 70 formed the cylinders can be very rapidly and cheaply made and made interchangeable with each other, thus enabling the number of tunes played by any one instrument to be increased indefinitely.

Having thus described our invention, we claim—

The process herein described of forming cylinders for musical instruments and other machines, consisting in forming a flat pattern, 80 then making a thin electrotype therefrom, and then bending this electrotype into a cylinder, substantially as shown and described.

In testimony whereof we affix our signatures in presence of two witnesses.

C. C. CARPENTER, 2d.
LUCIEN A. BROTT.
